US00D966270S

(12) **United States Design Patent** (10) **Patent No.:** **US D966,270 S**
(45) **Date of Patent:** **** Oct. 11, 2022**

(54) **DOCKING STATION**

(71) Applicant: **Shenzhen Colorii Tech Limited**,
Shenzhen (CN)

(72) Inventor: **Shu Jiang**, Guangdong (CN)

(73) Assignee: **SHENZHEN COLORII TECH
LIMITED**, Shenzhen (CN)

(**) Term: **15 Years**

(21) Appl. No.: **29/782,788**

(22) Filed: **May 10, 2021**

(51) LOC (13) Cl. **14-02**

(52) U.S. Cl.

USPC **D14/434**

(57) **CLAIM**

The ornamental design for a docking station, as shown and described.

DESCRIPTION

FIG. 1 is a left, top and front perspective view of a docking station showing my new design;

FIG. 2 is a right, bottom and rear perspective view of the docking station of FIG. 1;

FIG. 3 is a front view of the docking station of FIG. 1;

FIG. 4 is a rear view of the docking station of FIG. 1;

FIG. 5 is a left side view of the docking station of FIG. 1;

FIG. 6 is a right side view of the docking station of FIG. 1;

FIG. 7 is a top view of the docking station of FIG. 1;

FIG. 8 is a bottom view of the docking station of FIG. 1; and,

FIG. 9 is an exploded view of FIG. 1.

The broken lines in the figures illustrate portions of the article that form no part of the claimed design.

1 Claim, 9 Drawing Sheets
